UNITED STATES PATENT OFFICE.

OTTO F. FOGELSTRAND, OF KENSINGTON, CONNECTICUT, ASSIGNOR TO HART,
BLIVEN & MEAD MANUFACTURING COMPANY, OF SAME PLACE.

DESIGN FOR BOOT-JACKS.

Specification forming part of Design No. 6,896, dated September 30, 1873; application filed June 30, 1873.
[Term of Patent 7 years.]

To all whom it may concern:

Be it known that I, OTTO F. FOGELSTRAND, of Kensington, in the county of Hartford and State of Connecticut, have invented and produced a new and original Design for a Boot-Jack, of which the following is a specification:

The nature of my design is fully represented by the accompanying wood-cut, to which reference is made.

The contour of the jack proper A is of U-form, and is bordered by a raised ledge, inside of which is raised ornamental work. The contour of the foot-rest B is composed of curved and straight lines; is bordered by a raised ledge,

inside of which is raised ornamental work; and at the center there are ornamental openings. The surface of the neck C is fluted, all as shown.

I claim as my invention—

A design for a boot-jack, in which the surface of the jack proper, the neck, and the foot-rest is composed of raised work, ornamented substantially in the manner above described.

OTTO F. FOGELSTRAND.
